No. 727,197.

PATENTED MAY 5, 1903.

G. W. REYER.
NAME FASTENER.
APPLICATION FILED JAN. 26, 1902.

NO MODEL.

UNITED STATES PATENT OFFICE.

GUS W. REYER, OF STROUD, OKLAHOMA TERRITORY.

HAME-FASTENER.

SPECIFICATION forming part of Letters Patent No. 727,197, dated May 5, 1903.

Application filed January 25, 1902. Serial No. 91,282. (No model.)

To all whom it may concern:

Be it known that I, GUS W. REYER, a citizen of the United States, residing at Stroud, in the county of Lincoln and Territory of Oklahoma, have invented a new and useful Hame-Fastener, of which the following is a specification.

My invention is an improved hame-fastener; and it consists in the peculiar construction and combination of devices hereinafter fully set forth and claimed.

In the accompanying drawings, Figure 1 is a front elevation of the lower portion of a harness-collar, the hames thereon, and my improved hame-fastener, the latter being shown in its locked position. Fig. 2 is a detail perspective view of my improved hame-fastener, showing the lever thereof in unlocked position to enable the members of the fastener to be detached from each other. Fig. 3 is a sectional view of the same. Fig. 4 is a detail sectional view showing a portion of the lever and the spring-pressed locking-bolt thereon.

My improved hame-fastener is adapted to be used in connection with a collar *a* and hames *b* of the usual construction.

In the embodiment of my invention I provide a guide member 1, which is here shown as a tube curved to correspond with the curvature of the lower portion of the collar-flange *c* and having at one end, which I will call the "outer" end, a hook 2, whereby it may be attached to the lower end of one of the hames. On the upper side of the guide member 1 is a bearing-arm 3, which is curved to correspond with the curvature of the lower portion of the collar-flange *c* and bears directly under the latter, the said bearing-arm being spaced somewhat above the guide member 1 and at its outer end offset and secured thereto, as at 4. A tubular guide member has an opening 5 in its lower side near its inner end, which opening communicates with the bore thereof, and said tubular guide member is further provided at its inner end with a pair of lugs or ears 6, which extend downwardly therefrom, and on their inner sides are provided with notches 7. A lever 8 has its inner portion fulcrumed between the ears 6 on a stud, pin, or bolt 9, and the inner end of said lever is formed with a segment-pinion 10. Said lever has a longitudinal transversely-

extending slot 11 near its inner end beyond the radius of the lugs or ears 6, and in the said slot is disposed a locking-bolt 12, 55 which is movable axially therein, the ends of which project laterally beyond the sides of the lever 8 and are adapted to engage the notches 7, and which locking-bolt is provided with guide-arms 13 on its sides, which bear 60 on the sides of the lever 8 and close the sides of the slot 11. In the said slot is seated a spring 14, here shown as a coiled extensible spring, the function of which is to move the locking-bolt into engagement with the 65 notches 7 when the lever 8 is turned to such a position that the locking-bolt is disposed opposite said notches.

A member 15 is movable axially in the bore of the tubular member 1, is curved to correspond with said tubular member, and is provided at its outer end with a hook 16, whereby it may be attached to the other hame. On the under side of said axially-movable detachable member 15 are rack-teeth 17, and 75 the same are engaged by the segment-pinion 10, so that by moving the lever 8 in the direction indicated by the arrow in Fig. 2 said axially-movable rack member may be moved into the bore of the tubular member to draw 80 the hames tightly against the flange of the collar, and by the engagement of the locking-bolt 12 with the notches 7 said axially-movable member is locked in the tubular member when the lever 8 is in the position shown 85 in Fig. 1 and disposed under the axially-movable member. By reversing the position of the lever 8, which may be done after first disengaging the spring-pressed locking-bolt from the notches 7, the axially-movable member is run outwardly in the tubular member by the action of the pinion 10 and rack-teeth 17, and said segment-pinion finally disengages the racked axially-movable member, so that the latter may be completely detached from 95 the tubular member to detach the hames from each other. The bearing-arm 3 on the tubular guide member enables the latter to be held in such position with reference to the flange of the collar as to enable the axially-movable detachable member 15 to be readily inserted in the tubular guide member when securing the hames on the collar. Said bearing-arm is a spring which admits of the elas-

tic movement of the fastener under the collar-flange and a corresponding movement of the hames on the collar, which greatly facilitates the locking of the member 15 in the 5 guide-member 1 by the turning of the lever 8 to its locking position. The bearing-arm 3 is also useful when the fastener is employed on a collar which opens on its lower side, and when the fastener is thus used the bearing-arm 10 extends across the space between the sides of the collar.

Having thus described my invention, I claim—

15 A hame-fastener comprising a curved tubular guide member having means to attach it to one of the hames and having a spring-arm on its upper side to bear under the flange of

the collar, in combination with a curved cylindrical rack member movable axially in the guide member and having means whereby 20 it may be attached to the other hame, a lever pivotally connected to the guide member and having a segment-pinion to engage and disengage the rack member, and means to lock said lever and thereby secure said rack 25 member in and to the guide member, substantially as described.

In testimony that I claim the foregoing as my own I have hereto affixed my signature in the presence of two witnesses.

GUS W. REYER.

Witnesses:

PETER RENCH,
B. B. TYLER.
